US00D777141S

(12) **United States Design Patent** (10) **Patent No.:** **US D777,141 S**
Lee et al. (45) **Date of Patent:** **** Jan. 24, 2017**

(54) **REMOTE CONTROLLER**

- (71) Applicant: **Samsung Electronics Co., Ltd.**, Suwon-si (KR)
- (72) Inventors: **Young-Ah Lee**, Seoul (KR); **Jae-Yeop Kim**, Seoul (KR); **Kwan-Min Lee**, Seoul (KR); **Ji-Bum Moon**, Seoul (KR); **Jean-Christophe Naour**, Anyang (KR)
- (73) Assignee: **Samsung Electronics Co., Ltd.**, Suwon-si (KR)
- (**) Term: **14 Years**
- (21) Appl. No.: **29/485,985**
- (22) Filed: **Mar. 25, 2014**

(30) **Foreign Application Priority Data**

- Oct. 2, 2013 (KR) 30-2013-0050141
- (51) LOC (10) Cl. **14-03**
- (52) U.S. Cl. **USPC D14/218**
- (58) **Field of Classification Search**
USPC D14/218; D13/168, 154, 164, 162; D21/712; D10/106.1, 21, 6; D24/200; D9/430-433; 229/116; 473/595; 52/82, 72

Primary Examiner — John Windmuller*Assistant Examiner* — Luqman McNeil(74) *Attorney, Agent, or Firm* — NSIP Law(57) **CLAIM**

We claim the ornamental design for a remote controller, as shown and described.

DESCRIPTION

FIG. 1 is a rear perspective view of a remote controller showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the remote controller are for environmental purposes only and form no part of the claimed design.

1 Claim, 5 Drawing Sheets(56)
